[57] **CLAIM**

The ornamental design for a heater adapter for use with a floor type heating unit, as shown and described.

DESCRIPTION

FIG. 1 is a frontal perspective view of a heater adapter for use with a floor type heating unit showing my new design;

FIG. 2 is a top plan view;

FIG. 3 is a bottom plan view;

The undisclosed rear of the conical base shown in FIG. 1 is plain and unornamented.

FIG. 2

FIG. 1

FIG. 3
